UNITED STATES PATENT OFFICE.

PETER DHAENENS, OF MOLINE, ILLINOIS.

NUT LOCK.

Application filed October 29, 1927. Serial No. 229,719.

- This invention relates to the class of nut and bolt locks and pertains particularly to an improved means for locking a nut in position after the same has been tightened.
- 5 The primary object of the invention is to provide an improved means for locking a nut after the same has been tightened against a piece of work, in such manner that the nut may be easily released for removal.
- 10 Another object of the invention is to provide improved means for locking a nut, which is not dependent upon any cooperation from the bolt upon which the nut is threaded, the operating action being directly 15 between the nut and the work through which the nut-supporting bolt passes.
- The invention will be best understood from a consideration of the following detailed description taken in connection with 20 the accompanying drawings forming a part of the present specification, with the understanding, however, that the invention is not confined to any strict conformity with the showing of the drawings, but may be 25 changed or modified so long as such changes or modifications mark no material departure from the salient features of the invention as claimed.
- In the drawings:
- 30 Figure 1 shows the nut embodying the present invention, in side elevation and as applied.
- Figure 2 is a top plan view of the nut, a portion thereof being in section.
- 35 Figure 3 is a section taken upon the line 3-3 of Fig. 2.
- Figure 4 is a section taken upon the line 4-4 of Fig. 1.
- Figure 5 is a detailed perspective view 40 of a nut equipped with the locking device embodying a portion of the invention.
- Referring now to the drawings in detail, wherein like numerals of reference indicate corresponding parts throughout the several 45 views, the numerals 1 indicate a pair of plate members or other bodies through which a bolt 2 is passed, the shank of the bolt being provided at one end with the usual screw threads 3.
- 50 The nut structure embodying the present invention is indicated by the numeral 4 and is provided in one side with the recess 5, which recess extends transversely of the side and, as shown, joins an upwardly extending recess 6 which opens through the top face of the nut and is arranged in close proximity to
- one of the nut sides adjacent the side in which the recesses are formed.
- In the bottom 7 of the recess, directly in line with the upwardly opening passage 6, 60 an aperture 8 is formed which passes downwardly through the body of the nut and opens out through the bottom face thereof. As shown in Fig. 3, this passage 8 is of increased and constant diameter throughout 65 directly below the upper end, as indicated by the numeral 9, thus forming in the upper portion thereof a shoulder 10.
- Extending upwardly through the passage 8 from the lower end thereof is a pin 11, 70 the lower end of the pin being of a diameter to snugly fit in the enlarged lower portion 9 of the passage as indicated at 12. Surrounding the pin 11 and housed in the enlarged portion 9 of the passage is a coil 75 spring 13, the lower end of which rests upon the enlarged end or head 12 of the pin while the upper end bears against the shoulder 10. The upper end of the pin 11 is bent to extend at right angles to the passage 8 thus 80 forming an arm 14 which prevents the pin from dropping through the passage 8. This arm is normally housed in the recess 5 when the nut is in operative position, as shown in Fig. 1.
- When in use, that face of the piece of work 1 against which the nut must bear when tightened upon the bolt 2, is provided with an annular series of recesses 15 spaced the proper distance from the bolt hole to 90 receive the head 12 of the pin 11 when the nut has been tightened up a sufficient distance to permit the pin head to bear against the surface of the work. While the nut is being tightened to position, the arm 14 is 95 swung from its engaging recess 5 and the pin 11 drawn upwardly into the passage 6 so that the arm can be swung to engage over the top face of the nut thus drawing the head 12 into the enlarged portion 9 of the 100 passage 8 where it will be held free from contact with the work piece 1 until the nut has been sufficiently tightened, whereupon the pin can be released and permitted to engage in the nearest one of the recesses 15. 105 It will of course be understood that upon removal of the nut 4, the reverse manipulation of the pin 11 must be performed. The arm 14 is greater in length than the distance between the recess 6 and the adjacent side of 110 the nut 4, whereby to arrange its free end beyond said side when it is in contact with

the top face of the nut, and thus permit it to be conveniently grasped and manipulated to carry it into registration with the recess when it is desired to release the pin 11 for 5 projection into one of the recesses 15.

Figure 6 shows in detail perspective the nut per se, showing more clearly the manner in which the head portion of the pin 11 projects from the bottom face thereof.

10 From the foregoing description, it will be readily seen that the nut embodying the present invention may be readily employed in connection with any bolt of the proper size and from this it will be understood that 15 the manufacture of the present invention will be less expensive than is the case with the majority of locking devices wherein especially constructed bolts must also be employed in connection with the nut.

20 Having thus described my invention, what I claim is:—

A nut provided in one side thereof with right angularly related recesses, one recess extending transversely of said side and the 25 other being arranged adjacent another side

of the nut and extending from one end of said transverse recess to the top face of the nut, the nut being also provided with a passage arranged in alinement with said other recess and extending from the bottom face 30 wall of said transverse recess to the bottom of the nut, a shoulder arranged in said passage at the upper end thereof, a pin having a head at its lower end and slidably arranged in said passage, a spring surrounding said pin and bearing against said head and shoulder, and an arm carried by the upper end of said pin and housed in said transverse recess when the pin is in projected position and adapted to contact with the top 40 face of the nut when the pin is in retracted position, and said arm being greater in length than the distance between said other recess and said other side of the nut so as to arrange the free end portion thereof beyond 45 said other side of the nut when the pin is retracted.

In testimony whereof I affix my signature.

PETER DHAENENS.
